INTERLOCKING FINGER RING

William F. Roberts, Jr., Farmington, Mich., assignor to
Traub Manufacturing Company, Detroit, Mich., a cor-
poration of Michigan

Filed May 11, 1962, Ser. No. 70,085

Term of patent 14 years

(Cl. D45—10)

FIGURE 1 is a perspective view of an interlocking finger ring embodying my new design;

FIGURE 2 is a top plan view thereof;

FIGURE 3 is a left side elevational view thereof;

FIGURE 4 is a front elevational view thereof;

FIGURE 5 is a right side elevational view thereof;
and

FIGURE 6 is a sectional view taken substantially on the plane indicated by line 6-6 in FIGURE 4.

The characteristic features of the design reside in the portions shown in full lines in the drawing.

I claim:

The ornamental design for an interlocking finger ring substantially as shown and described.
